UNITED STATES PATENT OFFICE

2,444,200

RESTORABLE BLOWOUT INDICATING FUSE

J Edward Kostur, Amarillo, Tex.

Application August 6, 1943, Serial No. 497,662

2 Claims. (Cl. 200—121)

1

This invention relates to an electric fuse, and aims to provide a novel, efficient, simple, and durable construction in which a blownout condition will be indicated and which may be restored to condition for reuse by replacement of a fusible element.

It is especially aimed to provide a structure, attaining the end stated, which nevertheless is airtight, shockproof, and inexpensive.

It is particularly aimed to provide such a fuse having a removable elastic closure against which an element is moveable to bulge or distort it, and which normally is restrained against such function by the presence of a fusible element.

The more specific objects and advantages will become apparent from a consideration of the description following taken in connection with accompanying drawings illustrating an operative embodiment.

In said drawings:

Figure 1 is an end elevation of the fuse;

Figure 2 is a central longitudinal section taken on the line 2—2 of Figure 1;

Figure 3 is an enlarged fragmentary section taken on the plane of line 3—3 of Figure 2; and

Figure 4 is an enlarged detail section taken on the line 4—4 of Figure 2.

Referring specifically to the drawings wherein like reference characters designate like or similar parts throughout the different views, 10 represents a generally cup-shaped body of insulation of any suitable character such as glass, Bakelite, porcelain, or the equivalent. This body at one end has a wall 11 and at its other end is open, preferably having a reinforcing marginal ring or rim 12 with an interior shoulder 13 therein.

The fuse is constructed so as to be screwed into place like the ordinary or conventional fuses, in boxes, panels, or the like, and therefore has a central contact as at 14, and a screw-threaded shell as at 15.

The contact or conductor 14 is fastened in place in any suitable manner and usually screw-threaded to the end of a hook 16 at 17, the shank 18 of the hook being anchored in the wall 11 so that the hook 16 will be located interiorly thereof.

The shell or conductor 15 is fastened onto the side of cylindrical wall of the body 10 forwardly of the rim 12. A second hook is shown at 19 located interiorly of the body 10 at the free end of an inwardly or radially extending arm 20, whose outer portion is anchored in the body 10 and terminates in a corrugated portion 21 intimately fitted against the interior of the shell 15 and held in place between the same and the

2

body of insulation 10. The elements 19, 20, and 21 preferably are in a single piece and of conducting material and usually a length of metallic wire, so that the arm 20 unless restrained will assume or spring into the dotted-line position shown in Figure 2.

A fusible link provided at 22, being made of any conventional fusible material, usually primarily of lead, and adjacent its ends it has openings 23 whereby the same may be attached to the hooks 16 and 19. Such fuse is of sufficient strength, under normal conditions and when the parts are in conducting relation, to hold arm 20 retracted as shown in full-line position in Figure 1. However, when the fuse "blows" or is disrupted by short circuit, overload, or the like, arm 20 will be released and will spring to the dotted line position of Figure 2.

The open end of the fuse normally is closed in an air-tight manner and in such a way as to avoid shock or contact with any conducting parts, through the medium of a removable diaphragm disc 24 which preferably is of elastic material and primarily of rubber so as normally to assume the full-line position shown in Figure 2. Marginally the disc 24 preferably is strengthened by an enlarged bead 25. This bead is inserted into the rim 12 to bear against the inner surface of the latter and the shoulder 13, thus sealing the interior of the fuse. At the same time bead 25 is slightly oversized so that it will be compressed when engaged with the walls mentioned and will remain accordingly in place through its inherent expansion, although capable of being removed when desired. Since the disc 24 is elastic and expandable the arm 20, when sprung into dotted-line position shown in Figure 2, will bulge the disc so that its exterior surface will be irregular. Thus in the blowing or disruption of a fuse, the blownout condition will be indicated by the bulged condition of the disc and, if light is not available, such condition will be indicated in the dark by moving the hand or fingers over the disc.

It will be clear that upon removal of the disc 24 the disrupted fragments of the blown fuse will be removed, and new fusible elements or strips 22 may be used by hooking the same at openings 23 to the hooks 16 and 19.

It thus will be realized that the fuse, notwithstanding the novel advantages, nevertheless is safe for use even if subjected to inflammable gases, and also is shockproof, airtight, and inexpensive.

Various changes may be resorted to provided

that they fall within the spirit and scope of the invention.

I claim as my invention:

1. A fuse comprising a body of insulation, a contact jacket at the outside of the body, said body being hollow and provided with a centrally located contact at one end thereof, the other end of the body being provided with an internal shoulder, an annulus for snug disposition within the latter end of the body and against the shoulder, said annulus being provided with a flexible filler disc closing the adjacent end of the body, a fusible element, a pair of carriers for the fusible element, one extending inwardly from the jacket and the other inwardly from the contact, the carrier extending inwardly from the jacket being of spring material and adapted to spring outwardly to bulge the disc outwardly when disruption of the fusible element occurs.

2. A fuse comprising a body of insulation, a contact jacket at the outside of the body, said body being hollow and provided with a centrally located contact at one end thereof, the other end of the body being provided with an internal shoulder, an annulus for snug disposition within the latter end of the body and against the shoul-

der, said annulus being provided with a flexible filler disc closing the adjacent end of the body, a fusible element, a pair of carriers for the fusible element, one extending inwardly from the jacket and the other inwardly from the contact, the carrier extending inwardly from the jacket being of spring material and adapted to spring outwardly to bulge the disc outwardly when disruption of the fusible element occurs, said annulus and disc therein being removable from the body to permit replacement of a fusible element between said carriers.
